UNITED STATES PATENT OFFICE.

CARL DEUSCHLE, OF CINCINNATI, OHIO.

DISPLAY RACK.

Application filed August 13, 1926. Serial No. 129,070.

My invention relates to display racks for displaying goods, and is especially useful as a flower rack, to be used in connection with funerals or other occasions where a large 5 number of floral designs is to be displayed.

My improved rack is so constructed that it can be assembled without the use of tools, and can be arranged in knock-down relation and the parts packed together within comparatively 10 small compass of space, so as to be readily moved from place to place.

A serious problem in funerals is the proper display of floral tributes. The usual practice heretofore has been to arrange the 15 floral tributes or designs upon the mantle, the casket, various pieces of furniture and the floor, one tribute being often covered by another tribute so that a proper display of the floral tributes was not had.

It is the object of my invention to provide 20 a novel display rack of knock-down form, so that it may be easily carried from place to place; further, to provide a novel display rack which is readily assembled, preferably without the use of tools; further, to provide a novel display rack which is extensible so as to accommodate a greater or less number of articles, for instance floral tributes; and, further, to provide a novel 25 display rack for floral tributes which is extensible and collapsible, which may be readily assembled, for instance, at the late home of the deceased, or the church, and the floral tributes displayed thereon, and which may be quickly arranged in knock-down relation 30 for transfer to the cemetery, where it may be quickly reassembled for again receiving the floral tributes.

The invention will be further readily understood 35 from the following description and claims, and from the drawings, in which latter:

Fig. 1 is a front elevation of my improved device in assembled form, partly extended 40 and partly broken away.

Fig. 2 is a side elevation of the same.

Fig. 3 is a front elevation of the same in knock-down relation.

Fig. 4 is a plan view of the same in knock-down relation.

Fig. 5 is an end view of the same in knock-down relation.

Fig. 6 is a horizontal cross-section of a detail, taken on the line 6—6 of Fig. 1.

Fig. 7 is a horizontal cross-section of a detail, taken on line 7—7 of Fig. 1.

Fig. 8 is a vertical cross-section of a detail, taken on the line 8—8 of Fig. 1.

Fig. 9 is a vertical cross-section of a detail, taken on the line 9—9 of Fig. 1; and

Fig. 10 is a rear view of the releasable supporting connection between the sections of one of the rear legs of my improved device.

My improved display rack includes a stand which comprises a plurality of side frames 21. The side frames are respectively composed of sections, which have releasable connection therebetween, and are arranged to be collapsed for knock-down relation of the parts. One of these sections is shown as comprising bars 22, 23, connected at their front faces at top and bottom respectively by cross-strips 24, 25, of metal, screwed to the bars, these respective strips having overhanging lips 26, 27. The bars are connected at their rear faces by cross-strips 28, screwed to the respective bars. A space 29 is thus formed between said bars.

The other section of these side frames comprises a bar 31, which has releasable and preferably telescoping connection with its mating section, for arranging the sections in knock-down relation or in extended relation, as may be desired. This releasable connection is instanced as comprising a strip 32, of metal, secured to the bar 31, as by screws, this cross-strip having laterally extending lips 33 provided with notches 34, the walls of which are received under the heads of screws 35, screwed into the bars 22, 23. The bar 31 is also provided with a screw 36, the cross-strip 25 being provided with a notch 37, the wall of which is received under the head of the screw 36. These connections hold the bars in extended relations, and support the upper section upon the lower section of the side frame.

These bars and their connections form the front leg of the side frame. The rear leg of the side frame is similarly constructed, the upper section thereof comprising bars 42, 43, connected at their rear faces at the respective ends thereof by cross-strips 44, 45, and the lower section comprising a bar 46, the bar 46 being provided with a cross-strip 47 secured thereto, and provided with overhanging lips 48, provided with notches 49 received under the heads of screws 50, threaded into the bars 42, 43, the bar 46 being provided with a screw 51 and the cross-strip 45 being provided with a notch

52, the wall of which is received under the head of the screw 51, for arranging said sections in extended relations. The front faces of the bars are connected by cross-strips 53. 5 A space 54 is thus formed between the bars. These bars and their connections form the rear leg of the side frame. The sections may be arranged in telescoped knock-down relation, with the bar 46 received lengthwise 10 in the space 54.

The front leg and the rear leg of the side frame are connected together by means of a hinge 55.

A brace 56 is provided between the legs for 5 arranging the same in proper supporting relation. This brace is shown comprising strips 57, 58, hinged to the respective legs by screws 59, 60, and articulated to each other by a pivot 61, an overhanging end of one of the 20 strips being provided with a lug 62, received against the other strip, for placing said strips in bracing relation.

Cross-frames 71, 72, 73, connect the side frames of the rack, and are releasably secured thereto. The cross-frames are arranged one above the other on the stand. The cross-frame 71 is provided with side bars 75, 76, at the respective ends thereof, and arranged to be received respectively at 30 the inside face of the bar 22 and the outside face of the bar 23 for locating said cross-frames endwise. The side bars are connected by cross-bars 77, 78, to which the side bars are rigidly secured. The side bars extend 35 above the upper cross-bar and below the lower cross-bar for forming projections 80, 81. The upper projections 80 are received under the lips 26, and are arranged to be moved upwardly under said lips, due to the presence 40 of a space 82 between the cross-strips 24 and the cross-bar 77, for permitting the lower extensions of the side strips to be moved rearwardly past lips 83, fixed to the bars 22, 23, whereupon the cross-frame is moved downwardly along the bars 22, 23, for moving 45 the lower projections 81 of the side bars 75, 76, under the lips 83, the upward projections 80 thereof being sufficiently long to be positioned in rear of the lips 26 when the 50 lower cross-bar 78 will have engaged the lips 83. The lips 83 are secured to the bars 22, 23, respectively, by suitable screws.

The construction and arrangement of the cross-frame 72 is similar to that of the cross-frame 71, the parts being designated by similar reference numerals, with this difference, that the upward extensions 80 of the side bars are located in rear of lips 87, suitably secured to the bars 22, 23, the lower extensions of said side bars being received in rear of the lips 27.

The cross-frame 73 is similar in construction and arrangement of the cross-frame 71, the parts being designated by similar reference numerals, the positioning means of the

cross frame 73 being, however, shown different. These positioning means comprise strips 91, 92, secured to the respective side bars, these strips being provided with notches 93 for permitting the strips to be received under the heads of screws 94, 95, screwed into the bar 31. In this instance the side bars 75, 76, are closer together for accommodating the single bar 31.

The cross-frames are provided with display frames which are arranged to be placed in various positions with relation to the cross-frames, the cross-frames and display-frames being provided with attaching means for the goods to be displayed, which may be for instance floral tributes, the lateral positioning of the display frames outwardly in overhanging relations to the cross-frames increasing the display area of my improved device. Each of the cross-frames is shown provided with a pair of display frames 101, 102, which latter are arranged to be moved laterally outwardly for extending the effective area.

The display frames comprise side bars 105, 106, top bars 107 and bottom bars 108, suitably secured together preferably in such manner as to locate all these bars in the same plane of the display frame. The end bars are provided with projections 109 which are located across the ends of the bars 77, 78, when the frames are moved inwardly. The bars 105 are shown of greater width than the bars 107, 108, and are provided with lips 110 received in the rear of the bars 77, 78, and have lips 111 secured to their front faces, which are received in front of the bars 77, 78. This forms a slide connection at one end for the slide bar.

The rear faces of the top and bottom bars 107, 108, slide upon the side bars 75, 76, and the bars 22, 23, and 31, respectively. The upper face of the bar 107 and the lower face of the bar 108 are guided between the cross-bars 77, 78, and lips 112, secured to the cross-bars 77, 78, coact with the front faces of the bars 107, 108, for guiding the slide frame. Impingement of the bar 105 against the side bar 75 limits outward lateral movement of the slide frame.

The cross-frame and the slide frames are preferably provided with means for attaching the articles to be displayed, exemplified as hooks 115 on the cross-frame and hooks 116 on the slide frames. The hooks 116 may be located in blocks 117 secured to the slide frames.

In displaying floral tributes, the various floral pieces or designs may be attached to the hooks, or laid upon the frames, so as, if desired, to cover the entire display rack and hide the latter.

The area of display may be regulated by the extent of outward movement of the display frames, and a suitable number of cross-

frames may be employed, depending on the extent of display desired.

In arranging the display rack in knock-down relation, the slide frames are moved inwardly. The cross-frames 71, 72, are pushed upwardly to release the lower projections 81 from the lips 83 and 27 respectively, whereupon the lower ends of the cross-frames are pulled forwardly and downwardly for releasing the cross-frames from the stand. The cross-frame 73 is removed by pushing upwardly thereon and releasing the cross-strips 91, 92, from beyond the heads of the screws 94, 95, whereupon the cross-frame 73 is pulled forwardly for releasing it from the stand.

The legs of the stand are next collapsed, accomplished by pulling apart on the upper and lower sections thereof for releasing the heads of the screws 35, 36, from their coacting plates, and then pushing said sections together lengthwise for telescoping the same, and arranging the bar 31 in the space 29 between the bars 22, 23. The sections of the rear legs of said stand are similarly collapsed by releasing the cross-strips 45, 47, from the heads of the screws 50, 51, and then pushing the bars 42, 43, and the bar 46 lengthwise together, for arranging the bar 46 telescopically in the space 54 between the bars 42, 43.

The cross-brace 56, is also collapsed, whereby the collapsed front legs and rear legs of the stand may be folded together.

35 The frames 71, 72, 73, are arranged one upon another, and the collapsed legs are arranged lengthwise of said frames across one edge thereof, for compact arrangement of the parts in collapsed relation, in which relation they are readily received in a case, or a cover may be folded thereabout, the case or cover being provided with a suitable handle for ready carrying the display rack. The frame 72 may be provided with spacing blocks 118 for properly spacing the frames 72, 73, with relation to each other.

Having thus fully described my invention, what I claim as new, and desire to secure by Letters Patent, is:

50 1. In a display rack, the combination of a stand comprising a plurality of supporting members arranged side by side and collapsible with relation to each other, a plurality of cross-frames slantingly arranged one above another between said plurality of supporting members, releasable securing means between said cross-frames and said plurality of supporting members, oppositely laterally movable slantingly arranged display frames on said plurality of cross-frames, said cross-frames and said display frames arranged for display of goods thereon, and

adjustable connecting means between said display frames and said cross-frames for selective lateral overhanging relations of said display frames with relation to said cross-frames whereby to increase the display area of said display rack. 65

2. In a display rack, the combination of a stand comprising a plurality of supporting members, arranged side by side, said supporting members, respectively comprising a plurality of sections, releasable connecting means between said sections for arranging said sections in extended relation one above another, a plurality of cross-frames arranged one above another between said plurality of supporting members, releasable securing means between said cross-frames and said plurality of supporting members, laterally movable display frames on said plurality of cross-frames, said cross-frames and said display frames arranged for display of goods thereon, and adjustable connecting means between said display frames and said cross-frames for selective overhanging relations of said display frames with relation to said cross-frames whereby to increase the display area of said display rack. 75 80

3. In a display rack, the combination of a stand comprising a plurality of supporting members, each of said supporting members comprising a plurality of legs hinged together, each of said legs comprising a plurality of telescoping sections, releasable connecting means between said sections for arranging said sections in extended relation one above another, a plurality of cross-frames between said supporting members, releasable supporting and laterally holding connecting means between said cross-frames and said supporting members for arranging said cross-frames one above another on said supporting members and mutually bracing said cross-frames and supporting members, laterally movable display frames on said cross-frames, said cross-frames and said display frame arranged for display of goods thereon, and adjustable connecting means between said display frames and said cross-frames for selective overhanging relations of said display frames with relation to said cross-frames whereby to increase the display area of said display rack, said display frames and said cross-frames arranged to be 95 100

105 stacked one upon the other, and said sections of said plurality of supporting members collapsible and arranged to be placed lengthwise alongside said cross-frames for arranging said display rack in knock-down relation. 110 115

In testimony whereof, I have hereunto signed my name.

CARL DEUSCHLE.
